UNITED STATES PATENT OFFICE.

CARL VENDER, OF HOLTER, MONTANA.

TORPEDO-GUARD.

1,279,947.

Specification of Letters Patent. Patented Sept. 24, 1918.

Application filed August 25, 1917. Serial No. 188,147.

To all whom it may concern:

Be it known that I, CARL VENDER, a citizen of Switzerland, residing at Holter, in the county of Lewis and Clark and State 5 of Montana, have invented new and useful Improvements in Torpedo-Guards, of which the following is a specification.

This invention relates to torpedo guards and the object is to provide a series of guard 10 units which shall in a measure constitute an armor plating of special character adapted for the deflection of a torpedo from the sides of a vessel or for the explosion of said torpedo under impact with the plates constituting the protecting device.

A further object is to provide a series of pivotally or hingedly mounted plates which shall be carried by vertically disposed shafts at the sides of a vessel and which shall be 20 adapted for movement about said shafts as an axis, in order to reduce the resistance when the course of the vessel is changed from port to starboard.

A still further object is to provide a series 25 of guard units each carrying a vertically disposed shaft and a swinging guard member, with means for changing the elevation of the outer portions of the guard units and therefore of the plates, in order to raise the 30 guards from operative to inoperative position.

In the accompanying drawings:

Figure 1 is a view in side elevation showing the guard members in operative position.

Fig. 2 is a top plan view.

Fig. 3 is a further view in elevation of one of the guard units and showing a portion of the frame in section.

Fig. 4 is a detached view in perspective showing one of the guard plates and the means for directly supporting the latter.

Fig. 5 is a perspective view of one of the supporting elements.

The vertical shafts carrying the guard plates are designated 10, these shafts being mounted within blocks 12, which are in turn carried by the outer ends of arms 14 designed to project outwardly from the sides 50 of the vessel and to be maintained in a substantially horizontal position when the guard is in operative position. Bars 14 are pivotally mounted in brackets 15 secured to the sides of the vessel in order to permit the 55 raising of the guard members by means of any suitable apparatus. In the drawings I

have shown a plurality of connecting rods designated 16 which are pivoted at 17 and are adapted to elevate the frames and guard members, such frames including the outwardly extending bars 14 and the obliquely arranged bars or braces 20 which are pivotally connected at 21 with brackets 22 also secured to the sides of the vessel.

The guard members proper each comprise 65 plates 25 which may be termed armor plates, although it is of course understood that they are not sufficiently heavy in construction to add unnecessary weight to the series of guards mounted as herein described. Carried upon shafts 10 are tubular members 26 having outwardly extending flanges 27 spaced apart and inwardly turned as indicated at 28 for the purpose of providing engaging devices or jaws by means of which 75 the plates may be mounted and secured. The edge portions of the tubular member may be secured by rivets in any suitable manner. Each guard member or plate 25 is provided with a transversely extending 80 plate or strip 30 at one end thereof rigidly secured to the plate, by means of rivets or the like and designed to engage the flanged portions 27 above referred to. This construction permits the easy and prompt re- 85 newal of the plates or the individual plate members when damaged from any cause.

What is claimed is:

1. In a device of the class described, a plurality of members pivotally mounted on 90 the side of a vessel, a vertically located shaft supported by said members, a guard unit, and means for mounting the latter on the shaft, said means comprising a tubular member, and laterally and longitudinally 95 extending flanged portions thereon, said flanged portions being deflected forming an engaging device having oppositely located jaws, a member mounted on one edge portion of the guard unit and extending laterally therefrom and engaging the aforesaid jaws.

2. In a device of the class described, a guard unit, a shaft and means for mounting the latter in a substantially vertical position 105 at the side of a vessel, means carried by the shaft for supporting the guard unit and comprising a tubular member surrounding the shaft, and laterally and vertically extending flanged portions formed on the tubular member, said flanged portions being deflected outwardly and then inwardly form-

ing an engaging device, and means carried by and projecting from the guard unit for engaging the deflected portions.

3. In a device of the class described, a shaft and means for mounting the latter in a substantially vertical position at the side of a vessel, said mounting means comprising a plurality of outwardly extending arms pivotally connected with the sides of the vessel and blocks carried by certain of said

arms and provided with openings through which the shaft extends, a tubular member mounted on the shaft, laterally and longitudinally extending flanges carried by the tubular member, said flanges being deflected to form an engaging device, a guard unit and means carried thereby for co-operation with said engaging devices.

In testimony whereof I affix my signature.
CARL VENDER.
